UNITED STATES PATENT OFFICE

168,976

MOTOR VEHICLE COMPUTER

Robert K. Stortz, Waterford, Wis.

Application June 4, 1952, Serial No. 20,023

Term of patent 7 years

(Cl. D52—1)

To all whom it may concern:

Be it known that I, Robert K. Stortz, a citizen of the United States, residing at Waterford, in the county of Racine and State of Wisconsin, have invented a new, original, and ornamental Design for a Motor Vehicle Computer, of which the following is a specification, reference being had to the accompanying drawing, forming part thereof.

Figure 1 is a front elevational view of a motor vehicle computer showing my new design.

Figure 2 is a top plan view thereof; and

Figure 3 is a right end elevational view thereof taken from Figure 1.

I claim:

The ornamental design for a motor vehicle computer, as shown.

ROBERT K. STORTZ.
